UNITED STATES PATENT OFFICE.

SAMUEL L. HALSEY AND WILLIAM MCGHIE, OF NEW DECATUR, ALABAMA

SASH-WEIGHT MOLD.

SPECIFICATION forming part of Letters Patent No. 433,079, dated July 29, 1890.

Application filed April 19, 1890. Serial No. 348,608. (No model.)

To all whom it may concern:

Be it known that we, SAMUEL L. HALSEY and WILLIAM MCGHIE, citizens of the United States, residing at New Decatur, in the county 5 of Morgan and State of Alabama, have invented a new and useful Mold for Molding Sash-Weights, of which the following is a specification.

This invention relates to molds for molding sash-weights, and has for its object to construct a device of this class which shall possess superior advantages in point of simplicity and general efficiency.

The invention consists in the improved 15 construction of the said molds, which will be hereinafter fully described, and particularly pointed out in the claim.

In the drawings hereto annexed, Figure 1 is a perspective view of one-half of a mold 20 embodying our improvements, showing also the bottom plate of said mold in position for operation. Fig. 2 is a longitudinal sectional view of the mold complete, taken through one of the compartments of the said mold. Fig. 3 is a transverse sectional view taken on the line 3 3 of Fig. 2. Fig. 4 is a transverse 25 sectional view taken on the line 4 4 in Fig. 2. Fig. 5 is a perspective detail view of a sash-weight manufactured in one of our improved 30 molds. Fig. 6 is a perspective detail view showing the bottom of the mold detached.

Like numerals of reference indicate like parts in all the figures.

The mold which forms the subject of our 35 present invention is what is known as a "chill-mold." It is constructed of iron, in the usual manner of this kind of molds, and is composed of two parts or sections, both of which are constructed exactly alike and each of 40 which is designated by 1. Each of the sections 1 is provided with two longitudinal grooves or recesses, (designated, respectively, by 2 and 3,) and from each of said recesses a vent-groove 4 extends to the upper edge of 45 the mold. Between the recesses or compartments 2 and 3 is formed a flow-channel 5 for the admission of molten iron, said channel being enlarged at its upper end to form the pour-hole 6. Lateral branch channels 7 connect 50 the central channel 5 with the compartments 2 and 3, near the upper and lower ends of the latter, respectively.

The compartment 3 of each section 1 of the mold is provided near its lower end with a truncated projection 8, of suitable dimensions to reach the wall of the opposite compartment when the two sections 1 are placed together in position for operation. Each of the compartments 2 and 3 is provided with grooves or recesses 9, extending from their 55 lower ends to the lower edge of the mold-section 1. 10 designates a bottom plate, which is provided with truncated conical projections 11, adapted to enter through the openings formed by the opposing recesses 9 of the mold 60 and having oppositely-beveled upper ends adapted to bear against the undersides of the projections 8. The latter, in operation, serve to form the eye or opening through which the sash-cord is inserted and connected with the 65 sash-weight, the said cord being extended through the opening formed in the extreme upper end of the weight by the truncated cores.

The edges of the sections 1 of the mold are 70 provided with lugs 12 to enable the parts to be fitted together. The outer sides of the mold-sections are provided with handles 15, by means of which they may be conveniently 75 manipulated.

The operation and advantages of the invention will be readily understood from the foregoing description, taken in connection with the drawings hereto annexed. The mold-sections are placed together, the bottom plate 10 80 placed in position, and the molten metal is then poured through the opening 6 into the channel 5, whence it passes into the compartments 2 and 3 of the mold. The cores 8 and 11 serve to form the eyes in the weights, as 85 already described, and it will be observed that by each pouring a pair of weights are formed which may be afterward readily separated.

Heretofore it has been customary to mold 90 sash-weights in ordinary sand molds. This has been objectionable, partly on account of the expense of this class of molds and partly on account of the defective castings, which have always been more or less rough, notably 95 around the eyes for the attachment of the sash-cords, the result of which has been that said cords have been quickly cut and abraded, causing the weights to become detached. By 100

our improved molds smooth and perfect castings may be manufactured at a less expense than heretofore. Another advantage is that the molds, being of precisely the same size, there will be no perceptible difference in the weight of the castings.

Having thus described our invention, what we claim is—

In a chill-mold for making sash-weights, the combination of two similarly-constructed parts or sections, each having a longitudinal groove or recess provided with a vent-groove at its upper end, an intermediate pour-channel connected with said recess, an integral eye-core located near the lower end of one of said recesses and extending to the wall of the

corresponding recess in the opposite part or section, and grooves extending from the lower ends of said recess to the lower edge of the mold, and a bottom plate having truncated cores with beveled upper ends adapted to extend through said bottom grooves and to bear against the under sides of the eye-cores, substantially as and for the purpose set forth.

In testimony that we claim the foregoing as our own we have hereto affixed our signatures in presence of two witnesses.

SAMUEL L. HALSEY.
WILLIAM MCGHIE.
